UNITED STATES PATENT OFFICE

JOHN A. BETTIN, OF LOS ANGELES, CALIFORNIA, ASSIGNOR TO EMMA A. BETTIN, OF LOS ANGELES, CALIFORNIA

CONVEYER

Application filed August 6, 1927. Serial No. 211,027.

This invention relates to conveying, hoisting and elevating machinery and the like; the invention consisting of certain improvements in the structure and design of a material handling device of the chain bucket type.

Heretofore so far as I am aware devices of the type and character herein referred to have consisted of a carrier chain or belt or the like with buckets or scoops mounted and carried thereon, such buckets or scoops being usually secured to the chain or belt in such a manner and position as to overhang from the chain or belt. Such a design and construction is essentially weak as it puts the load, or strain resulting from excavating or load picking up operations, at a considerable distance from the point of support of the bucket or scoop.

It is an object of my invention to provide a novel design wherein such difficulties are completely overcome, and furthermore to provide a construction wherein the bucket or scoop forms an operative element of the chain or belt construction, in such a manner that the bucket or scoop may be supported directly from the sprockets instead of being indirectly supported therefrom through the medium of the chain or belt structure.

Such objects and others and the corresponding advantageous characteristics flowing from my invention will be best understood from the following detailed specification wherein I describe a typical and preferred construction embodying the invention, reference for that purpose being had to the accompanying drawings, in which:

Fig. 1 is a side elevation of a conveying or hoisting mechanism embodying my invention;

Fig. 2 is a front elevation of the same;

Fig. 3 is an enlarged sectional detail on line 3—3 of Fig. 2;

Fig. 4 is a section on line 4—4 of Fig. 3;

Fig. 5 is a fragmentary side elevation of conveying or hoisting mechanism showing a modified construction.

Fig. 6 is a front elevation of the parts shown in Fig. 5;

Fig. 7 is an enlarged end view of a single bucket.

Fig. 8 is a plan of the same; and

Fig. 9 is an enlarged fragmentary front elevation with parts in section.

It will be understood from what follows that my invention may take many specific forms; that the advantages and utilities of my invention are applicable to mechanisms which function only as material conveyors as well as to mechanisms which function additionally as excavators or as hoists which pick up material at the lower end. However the full features of my invention are best explained with reference to a conveyer of the hoist or excavator variety and the invention will therefore be specifically explained in that form, although without necessary limitation thereto.

The typical form of mechanism shown in the drawings embodies an upper pair of driving sprockets 10 and a lower pair of idler sprockets or rollers 11, the shafts of these pairs of sprockets being structurally connected by a framing 12 provided with a take-up device 13, all as will be well understood, without the need of further detailed explanation. The driving sprockets 10 will preferably be provided with teeth 14 of suitable form for driving the conveyer chain, but the sprockets or rollers 11 need not be provided with driving teeth, unless they are also utilized as driving sprockets. In a typical installation the elements 11 will constitute only idlers, but will preferably be provided with properly spaced peripheral recesses 15 to take and properly support the scoops or buckets 16, the shape of the recesses being thus dependent upon the cross-sectional configuration of the scoops. In the present instance I have shown the scoops as being substantially circular in cross sectional form, but it will be understood that these scoops may be of any desired form and size, both as to cross section and as to their longitudinal extent.

It is a characteristic feature of my invention that these scoops 16 form in effect elements of the composite chain or belt which comprises the material carrying unit of the

device. In the simple form shown in Figs. 1-4 the composite chain is made up of two series of side links 20. One end of each link 20 is pivoted to the other end of the next adjacent link on a suitable pivot pin 21. This pivot pin 21 in the preferred construction here illustrated extends not only through both the links but also extends through reinforcing end block 22 of the scoop 16, substantially in line with the central horizontal axis thereof. The scoop 16 with its reinforcing end block 22 is rigidly attached to the end 20^a of a link 20 (see Fig. 4) and this, in the preferred construction shown in the drawings, is done by riveting with rivets 23 which extend through the end wall 24 of the scoop, through the reinforcing end block 22 and through portion 20^a of the link 20. However, any form of connection will suffice that prevents the bucket from rotating back from its digging or pick-up position. Each end of the scoop 16 is thus securely and rigidly attached to one end of a link 20 and each end of the scoop is reinforced and strengthened by the end block 22 where it rides upon the sprockets or rollers, as the idling sprocket 11 shown in part in Fig. 4. The body of the scoop 16 itself may bear upon the sprocket or roller; but it is preferred to give it a reinforcing as described at its end so that the body of the scoop need not be constructed of any heavier material than is necessary for the service to be performed. The reinforcing end block 22 may be regarded as a part of the scoop; and whether or not such a reinforcing end block is used it will be seen that the scoop is directly supported from the sprocket or roller, and forms in effect the element of the chain combination which directly rides the sprockets or rollers. The pivotal point of connection between adjacent links, at the pin 21, is concentric with the scoop and its reinforcing end block 22, as best shown in Fig. 3.

The material carrying course of the composite chain may be supported, if desired, upon any suitable ways or guides, for instance the guides or ways 30 as shown in Fig. 1.

Suppose now that the mechanism shown in the drawings is being used as a hoist or excavator. The mechanism so operating to make the chain travel in the direction indicated by the arrows and each scoop, as it travels around the lower end, scoops up or excavates its quota of material, filling with material as it passes around the lower idlers. During this travel the scoop is directly and positively supported by the idlers and is thus supported in a manner such as to relieve to a very large degree all the strains to which an ordinary scoop is subjected. During the scooping action the scoop is pre-

vented from rotating about its own axis by reason of its rigid attachment to the links 20. But the strain thus exerted on the links is much less than is the case in any ordinary construction, because in my construction the links are attached to the center of each scoop and not to the back side of each scoop, as is usually the case. And the strain of keeping the scoops from rotation is the only strain placed upon the links; all of the direct pressures generated in the excavation or pick-up of material being transmitted directly through the scoop to the idlers upon which the scoops are directly supported.

In Figs. 5 to 9 I illustrate the same general assembly as before described, but with a bucket or scoop design in modified detail. Here the bucket has a body 16^a with faces along its edge and ends at 16^b, 16^c for the mounting of digging or excavating teeth 16^d and 16^e and is also provided at its ends with offset or projecting cylindric faces 50 which form the surfaces that bear upon the faces of the sprockets and idlers. The ends of the buckets are so made up and designed that the ends are considerably reinforced by the same formation that forms the cylindric faces 50. With these bearing faces thus formed, the shape of the bucket body 16^a itself may be anything desired, a typical form being shown in the drawings.

The two end faces 51 of the bucket may then be provided with a raised seat 52 upon which one end 20^e of a link 20^b is seated, being held by a bolt 53. To prevent the bucket turning back with relation to the link end 20^e the seat 52 may be provided with a side lug 54 against which one edge of the link will rest. The extreme end of this link extends to a point opposite the center axis of the bucket (the center of the cylindric surface 50) and has a hole 55 adapted to receive one end 56 of a hub or boss on the adjacent end 20^f of the adjacent link 20^d. The other side 56^a of this hub or boss fits into a hole 55^a in the end of the bucket. Thus the end 20^f of that link is pivotally connected with the bucket and with the end 20^e of the first mentioned link. It will be seen from an inspection of Fig. 9 how the formation allows link end 20^e to overlie link end 20^f, so that link end 20^f lies between link end 20^e and the end surface 51 of the bucket. A bolt 57 may be used to hold the parts together, not necessarily to form a pivot but only for the purpose of preventing any accidental or forceable displacement of the parts.

From a consideration of the modified structure it will be understood that the invention is not limited to any particular relative design or shape of parts but may be applied to many varying specific designs. It will also be understood that the function

performed by rigidly attaching the bucket to one end of the link is primarily that of preventing the bucket from backing around under strains of digging or picking up material—for instance to prevent a left hand rotation in Fig. 3 or Fig. 7. The specific construction so far described will prevent relative rotation of the bucket in either direction; but for instance if in Fig. 7 the bolt 53 is removed then it will be seen that the lug 54 will prevent left hand rotation of the bucket relative to link end 20° but will allow relative right hand rotation. And in some cases this may be desired for the purpose of tipping the bucket to facilitate discharge.

I claim:

1. A conveyer mechanism embodying, in combination, a sprocket-shaped rotating member and a composite conveyer chain adapted to pass around that member, said composite conveyer chain comprising scoops contacting directly with the rotating member at the recessed portions thereof, and interconnecting links between the scoops, each scoop being non-rotatively connected to one end of an interconnecting link.

2. A conveyer mechanism embodying, in combination, a sprocket-shaped rotating member and a composite conveyer chain adapted to pass around that member, said composite conveyer chain comprising horizontal scoops contacting directly with the rotating member at the recessed portions thereof, and interconnecting links between the scoops, said interconnecting links being pivotally connected together substantially at the central horizontal axis of the scoops, and each scoop being non-rotatively connected to one end of an interconnecting link.

3. A conveyer chain construction embodying the combination of a plurality of transversely extending scoops, and a plurality of pivotally interconnected longitudinally extending links in two sets, one at each end of the scoops and at the outside thereof, the links of each set being pivotally interconnected substantially on the transverse central axis of the scoops, and each scoop being rigidly connected with an end of one of the links which are so pivotally interconnected at its axis.

4. A conveyer chain construction embodying the combination of a plurality of transversely extending scoops, and a plurality of pivotally interconnected longitudinally extending links in two sets, one at end of the scoops and at the outside thereof, the links of each set being pivotally interconnected substantially on the transverse central axis of the scoops, and each scoop being rigidly connected with an end of one of the links which are so pivotally interconnected at its axis, the end of each scoop being rein-

forced and presenting a bearing surface adapted to ride a rotating member.

5. A conveying mechanism, comprising in combination a pair of transversely spaced rotating members, a plurality of transversely extending scoops comprising end walls provided with reinforcing formations adapted to ride the rotating members, the scoops being thereby directly supported upon the rotating members, and two sets of longitudinally extending and pivotally interconnected links, the links of each set being pivotally interconnected at points at the end of and substantially on the transverse central axis of the scoops.

6. A conveying mechanism, comprising in combination a pair of transversely spaced rotating members, a plurality of transversely extending scoops comprising end walls provided with reinforcing formations adapted to ride the rotating members, the scoops being thereby directly supported upon the rotating members, and two sets of longitudinally extending and pivotally interconnected links, the links of each set being pivotally interconnected at points at the end of and substantially on the transverse central axis of the scoops, and an end of one such link being non-rotatively connected with an end of a scoop.

In witness that I claim the foregoing I have hereunto subscribed my name this 8 day of July, 1927.

JOHN A. BETTIN.
